UNITED STATES PATENT OFFICE.

CHARLES W. COLLER AND JOHN S. NAERY, OF LAFAYETTE, INDIANA.

DESIGN FOR A FOOT-PLATE FOR CARS.

SPECIFICATION forming part of Design No. 32,544, dated April 17, 1900.

Application filed March 21, 1900. Serial No. 9,612. Term of patent 3½ years.

To all whom it may concern:

Be it known that we, CHARLES W. COLLER and JOHN S. NAERY, citizens of the United States, residing at Lafayette, in the county 5 of Tippecanoe and State of Indiana, have invented and produced a new and original Design for a Foot-Plate for Cars, of which the following is a specification, reference being had to the accompanying drawings, forming 10 part thereof

Referring to the accompanying drawings, Figure 1 is a plan view showing our new and original design for foot-plates for cars. Fig. 2 is a front elevation. Fig. 3 is a sectional plan view on the line 3 3, Fig. 2, looking in the direction of the arrow; and Fig. 4 is a transverse sectional view on the line 4 4, Fig. 2.

The essential feature of our new and original design for foot-plates comprises two members arranged substantially parallel to each other, one member of which is provided with bosses near its ends, while the other member has inturned flanges bearing against the rear face of the first member and has open spaces 25 between the ends.

Referring to the drawings, A and B are the two members, substantially parallel to each other. The member A has near each end a projecting boss a a' , with tapering ribs a^2 extending from the sides of the bosses. The 30 other member B has inturned flanges b b' b^2 on three of its sides, projecting toward and bearing against the rear face of the member A. There are open spaces B^2 B^3 , with an extending tongue or flanged portion b^3 near the 35 longitudinal center of this member.

What we claim is—

The new and original design for a foot-plate for cars, substantially as shown and described.

In testimony whereof we have signed our 40 names to this specification in the presence of two subscribing witnesses.

CHAS. W. COLLER.
JOHN S. NAERY.
